(57) CLAIM

I claim the ornamental leg assembly for furniture, as shown.

DESCRIPTION

FIG. 1 is a front side perspective view of an article of furniture, namely, a chair, embodying the ornamental leg design comprising the present invention;

FIG. 2 is a front side elevational view thereof;

FIG. 3 is a left side elevational view thereof;

FIG. 4 is a rear side elevational view thereof;

FIG. 5 is right side elevational view thereof; and,

FIG. 6 is a bottom perspective view thereof.
